CONVERTIBLE SOFA

Louis Robinson, Detroit, Mich.

Application June 9, 1948, Serial No. 31,950

4 Claims. (Cl. 5—21)

1

This invention relates to convertible combinations of sofa and bed, and more particularly to a sofa construction which is readily convertible to a full sized double bed.

Heretofore various constructions have been provided for converting the sofa to a single or one and a half size bed, however it is the principal object of this invention to provide a novel sofa construction which is convertible to a full size double bed as and when desired.

It is the further object of this invention to provide a secondary bedspring and mattress support which is normally stored in a lowered position beneath and within the sofa construction, but which is adaptable for transverse outward movement therefrom, said secondary bedspring and mattress support including operative mechanism which will hold the same in its lowered inoperative position, but which is also adapted to effect upward adjustment thereof for bringing the same into alignment with the corresponding mattress support which forms a part of the couch itself.

These and many other objects will be seen from the following specification and claims in conjunction with the appended drawings in which:

Figure 1 is a perspective view of the convertible couch and bed, with the couch backrest elevated to a substantially vertical position to provide a single bed.

Figure 2 is an end elevational view of the couch but with a side arm removed to show the construction of the secondary spring and mattress support and its positioning within the couch base.

Figure 3 is a similar view, but showing the secondary mattress support moved outwardly from the frame of the couch and elevated to its operative position.

Figure 4 is a partially sectioned plan view taken on line 4—4 of Figure 3.

Figure 5 is a fragmentary plan section taken on line 5—5 of Figure 3.

Figure 6 is an elevational section, fragmentarily shown, on line 6—6 of Figure 3.

Figure 7 is a fragmentary plan view taken on line 7—7 of Figure 2.

It will be understood that the above drawings illustrate merely a preferable embodiment of the invention, and that other embodiments are contemplated within the scope of the claims hereinafter set out.

Referring to Figure 1 the convertible couch is shown including spaced side arms 11 and 12, the

2

covered mattress support 25, with mattress 14 thereon, and the upright back element 15.

Back rest 16 is shown in a retracted elevated position resting and retained within the rearwardly extending recessed portions 17 of the blocks 18 which are secured to the interior rear portions respectively of side arms 11 and 12.

As shown in Figure 2 the upper end of backrest 16 is hinged at 13 to the normally horizontal straight topped element 19, which in turn is hingedly joined at 20 to the upper portion of the couch back 15.

When used as a couch back top 19 will be in a horizontal position with its forward portion resting upon the peak 21 of block 18 and with back rest 16 bearing against the inclined rearwardly extending edge 22 also forming a part of block 18. It is contemplated that there are two of such blocks, and that the respective opposite ends of back top 19 as well as back rest 16 are adapted for cooperative engagement with the surfaces of said blocks.

It will be seen that with the back rest 16 and flat topped portion 19 pivoted and elevated to the vertical position shown in Figures 1 and 2, the couch is now converted for use as a single bed.

Referring to Figures 3, 5 and 6 right angled supports 23 are respectively secured in a horizontal position to the interior walls of side arms 11 and 12 by means of the screws 24. A hollow rectangularly shaped spring frame 25 including the crossed spring elements 26, is positioned between side arms 11 and 12 and against the back 15, and rests at its ends upon right angle supports 23.

Spaced centering pins 27 project downwardly from end portions of spring support 25 as shown in Figures 3 and 6 and are adapted for cooperative retaining registry within corresponding spaced vertical openings in the inwardly projecting flanges which form a part of supports 23.

By this construction mattress support 25 is positioned and retained in its proper position with respect to the side arms and back portion of the convertible couch, and the conventional suitably covered mattress 14 is positioned upon support 25—26 as best seen in Figures 1 and 3.

A secondary hollow rectangularly shaped mattress support 29 including the suspended intersecting spring elements 30 is positioned in a lowered position directly below the couch spring support 25 as shown in Figure 2. This support rests upon rollers 30' upon the floor upon which the couch is mounted, and is adapted to be rolled

outwardly from the front part of the couch and be elevated to the position shown in Figure 3, a suitable mattress 31' being provided for positioning thereon and in alignment with the conventional couch mattress 14 to thereby provide a 5 complete double sized converted bed.

As viewed in Figures 3 and 4 two pairs of crossed legs 28 and 31 are each centrally pivoted at 32, one pair being arranged at each end of secondary spring 29-30, being pivotally joined 10 thereto at points 33 and 34 at their upper ends.

The pivotal supports 33 for the legs 28 at opposite ends of spring 29-30 are substantially stationary being mounted upon the flanged elements 35 which are suitably secured and project 15 inwardly of its ends to provide clearance for the other pivotal legs 31.

The upper ends of each of the legs 31 have an outwardly projecting guide pin which is the 20 aforesaid pivotal support 34, said pins extending through the longitudinal slots 35 formed within the rear ends respectively of said spring. As shown in Figure 2 the legs 28 and 31 are collapsed towards a horizontal position so that the 25 supporting pins 34 are mechanically moved rearwardly within the corresponding slots 35, as contrasted with their forward position therein as shown in Figure 3.

A strong coiled spring 36 is interposed between the upper ends of the collapsible legs 28 and 31 being respectively secured thereto at points 37, said spring being in its normal unexpanded position in Figure 3. However, in the collapsed position of legs 28 and 31 both of the 35 coiled springs 36 at opposite ends of spring 29-30 are substantially elongated and stretched to the point that when the spring frame 29 is moved outwardly and released said frame will automatically assume the elevated position 40 shown in Figure 3.

A short link 38 is joined at one end to the supporting pins 34 on the outside of frame 29 with its other end pivotally joined at 39 to a central portion of the lever 40. One end of said lever is pivotally joined at 41 to the end of frame 29 while its other end is pivotally joined at 42 to the inner end of the actuating lever 43.

The outer end of lever 43 is in turn pivotally joined at 44 to the operating lever 45, whose 50 other end is pivotally joined at 46 to the normally vertical secondary spring operating board 47. As shown in Figure 2 the board 47 is hingedly joined at 48 to the outer end of secondary frame 29 and is in upright position projecting above the same. At the same time the two levers 45 and 43 are in longitudinal alignment with their oppositely extending formed end elements 49 and 50 cooperatively engaging each other as shown in Figure 7 to prevent further pivotal movement of said levers about their common connection 44.

Referring to Figure 3 it is seen that frame 29 has been moved outwardly from under the sofa proper upon rollers 30 at the lower ends of supporting legs 28 and 31, and has been permitted to assume the elevated position shown with operating board 47 having been rotated 180 degrees to the position shown.

In this position it will be seen that link 38 has moved forwardly from the position shown in Figure 2 and the short lever 40 has pivoted in a clockwise direction in excess of 90 degrees. The connecting end at 42 of lever 43 is elevated as shown in Figure 3, and by action of the oper-

ating board 47 in being manually rotated 180 degrees, said long lever 43 has been forwardly projected till its outer end at 44 is positioned at the end of frame 29, and at the same time operating lever 45 has assumed a vertical position.

As shown in Figures 2 and 3 the short connecting link 38 has a central concave portion 51 which permits said link to clear the pivotal connection 41 as lever 40 and said link are moved forwardly in the opening of the secondary frame 29.

By downwardly swinging the board 47 from the position shown in Figure 2 the alignment of lever elements 43-45 is broken and the legs are released so that the coiled springs 36 are now effective causing frame 29 to elevate.

The mattress 31' which is carried upon frame 29 is normally positioned below the sofa proper when not in use with its weight tending to partially counterbalance the coil springs 36 which in the position of the removable element of Figure 2 are substantially extended.

Referring to Figure 3 the weight of mattress 31' assists in downwardly projecting the frame work 29 towards the floor against the action of springs 36. In the lowered position the board 47 has been swung to a vertical position as shown in Figure 2 and by the arrangement of the levers 45 and 43 will remain in said lowered position until and unless released by downward swinging of the control board 47.

Spacer bar 52 is interposed between side arms 11 and 12 at their lower rear portions, there being a longitudinal slot 53 formed therein at one end. 35 A corresponding spacer bar 54 is joined to and interposed between the lower ends of the corresponding rearwardly extending legs 28 of the removable element, said spacer 54 being similarly and correspondingly slotted at 55.

A pair of cross bars 56 and 57 are centrally and pivotally joined to each other at 58 with one end of bar 56 anchored to the spacer bar 52 at the end thereof opposite to its slot 53. The other end of bar 56 has a downwardly extending element 59 shown in Figure 3 which guidingly and retainingly extends within longitudinal slot 55 in spacer 54.

Similarly one end of bar 57 is swivelly anchored at 60 to the end of spacer 54 opposite from its slotted portion, with the other end of bar 57 having a downwardly extending retaining element 61 Figures 2 and 4 which guidingly and retainingly projects within slot 53 of spacer 52. Consequently bars 56 and 57 cooperate to limit the outward adjustment of the frame 29 maintaining the same in parallel relation to the couch frame 25, the respective ends of said rods sliding outwardly within slots 53 and 55 as frame 29 is returned to the position shown in Figure 2.

Having described my invention, reference should now be had to the claims which follow for determining the scope thereof.

I claim:

65 1. In a collapsible mattress support, a pivotally joined pair of crossed legs at each end thereof, resilient means interconnecting the legs of each pair above their juncture, one of each of said pairs of legs being pivotally joined to said support with the other slidably joined thereto, permitting vertical adjustments of said support while remaining in a horizontal position, a vertically positioned front board pivotally joined to said support along its front longitudinal edge, and a 70 toggle linkage interconnecting said board and the 75

sliding connection of said legs to control vertical movements of said support.

2. In a collapsible mattress support, a pivotally joined pair of crossed legs at each end thereof, resilient means interconnecting the legs of each pair above their juncture, one of each of said pairs of legs being pivotally joined to said support with the other slidably joined thereto, permitting vertical adjustments of said support while remaining in a horizontal position, a vertically positioned front board pivotally joined to said support along its front longitudinal edge, and a toggle linkage interconnecting said board and the sliding connection of said legs, whereby said board extends upwardly from its pivotal connection when said support is vertically collapsed, but extends downwardly therefrom when said support is vertically expanded.

3. In a vertically collapsible mattress support, a pivotally joined pair of crossed legs pivotally joined to said support at each end thereof, coiled springs interconnecting upper portions of the legs of each pair, there being a sliding connection between said support and one of each of said pairs of legs, a vertically arranged board pivotally joined to the front longitudinal edge of said support, and a toggle linkage interconnecting said sliding connection and said board, whereby when the latter is positioned above its pivotal connection said linkage will be effective to lock said support in a vertically lowered position, but which when pivoted below its pivotal connection, said linkage will be effective to permit said coiled springs to cause an automatic upward adjustment of said support.

4. In a convertible sofa and bed including a mattress support, a second horizontally arranged mattress support normally positioned under said first support, a pivotally joined pair of crossed legs at each end of said second support, resilient means interconnecting the legs of each pair of legs above their juncture, one of each of said pairs of legs being pivotally joined to said second support with the other slidably joined thereto, 10 permitting vertical upward adjustments of said second support when removed from under said first support, a vertically arranged front board hingedly joined to the front horizontal portion of said second support, and a toggle linkage interconnecting said board and the sliding connection of said legs, whereby upon pivotal 90 degree downward movement of said board, said linkage is released to permit automatic upward expansion of said second support by said resilient 20 means, and upon a further 90 degree downward movement of said board said linkage will be effectively locked to retain said second support in its upwardly adjusted position.

LOUIS ROBINSON.
